By *A. S. Sprague, Atty.*

UNITED STATES PATENT OFFICE.

ISAAC W. NEWMAN, OF CLEVELAND, OHIO.

BICYCLE-LOCK.

SPECIFICATION forming part of Letters Patent No. 598,326, dated February 1, 1898.

Application filed June 18, 1897. Serial No. 641,258. (No model.)

To all whom it may concern:

Be it known that I, ISAAC W. NEWMAN, a citizen of the United States, residing at Cleveland, in the county of Cuyahoga and State of Ohio, have invented certain new and useful Improvements in Bicycle-Locks, of which the following, with the accompanying drawings, is a specification.

This invention relates to certain new and useful improvements in bicycle-locks.

The object of the invention is to provide a lock designed to be secured upon the frame of the bicycle in such position that its locking-bolt may be projected between the spokes 15 of the sprocket-wheel, so as to prevent the latter turning.

The invention consists in the novel features of construction and in the various combinations of the parts, all as more fully hereinabove described, and pointed out in the claim.

In the accompanying drawings, which form a part of this specification, Figure 1 is a side elevation showing a portion of a bicycle-frame, the pedal-sprocket, and my improved lock in place. Fig. 2 is a top plan of same. Fig. 3 is an enlarged perspective of the lock detached. Fig. 4 is a central longitudinal section through the lock, the parts being in their unlocked positions. Fig. 5 is a similar view 30 locked. Fig. 6 is an end elevation with the key removed. Fig. 7 is a cross-section on the line $x-x$ of Fig. 1. Fig. 8 is a perspective view of the key.

A represents a suitable cylinder, open at one end to receive the plunger-cylinder B, which is adapted to freely slide therein.

C represents a cross-head adapted to slidely engage the plunger-cylinder B, and it is provided with a rod D, which passes through 40 the inner head a of the plunger-cylinder B and is rigidly secured in any convenient manner to the head of the cylinder A.

E is a coil-spring around the rod D, between the head a of the plunger-cylinder and the cross-head C.

In the outer end of the plunger-cylinder B is rigidly secured a casting F, preferably of aluminum. Near the inner end of this casting there is formed a transverse recess b to 50 receive the locking bolt or tumbler G, and H is a spring, one end of which is rigidly secured to the casting F, its free end resting

upon the head of such tumbler G. Through the longitudinal center of the casting F is formed a keyhole c to receive the key J, and 55 a keyway d is formed in the tumbler G. The outer end of the key is provided with a head K.

In one side and in the longitudinal direction of the cylinder A is formed a depression e, which extends to within a short distance of 60 its open end and terminates in a shoulder f. The inner end of the plunger-cylinder B is similarly formed, so as to engage or register with such depression, as is clearly shown in Figs. 4 and 5, and the outer end of such cylinder B is provided with a lip L.

The device is designed to be secured by clips or other suitable and convenient means to the lower bars M of a bicycle-frame in any such manner as will admit of the projecting 70 of the plunger-cylinder between the spokes of the sprocket-wheel N, as hereinafter described.

The parts being constructed and arranged substantially as herein set forth the operation is as follows: When it is desired to lock the wheel, the rider by means of the lip L draws the plunger-cylinder outwardly with its free end projecting between the spokes of the sprocket-wheel and until the spring H 80 forces the tumbler outwardly to engage with the stop or shoulder f of the cylinder A, such action compressing the spring E, as shown in Figs. 2 and 5. He now withdraws the key and can leave his wheel, confident that no one 85 can "run" it away. By inserting the key and turning it until its ward engages with the tumbler G and raises it from its engagement with the stop or shoulder f the spring E exerts its force and retracts the plunger-cylinder 90 within the cylinder A, as shown in Fig. 4, and when the parts are in this position the key cannot be withdrawn.

While I have shown but one tumbler G, it is evident that two or more may be employed 95 without departing from the spirit of my invention, and I do not desire to confine myself to the location of the lock upon the bicycle, as it may be placed on top of the bars M or be adapted to engage with either of the wheels. 100

What I claim as my invention is—

A bicycle-lock consisting of an outer cylinder A, having the internal stop f, a plunger-cylinder B, slidely engaging said outer cyl-

inder, a casting F, rigidly secured in said cylinder B, and provided with a tumbler G, adapted to engage the stop f, a rod D, having a cross-head C, a spring E between said cross-head C and the head a of the plunger-cylinder B, the parts being constructed, arranged and operating substantially in the manner and for the purpose specified.

In testimony whereof I affix my signature, in presence of two witnesses, this 26th day of 10 May, 1897.

I. W. NEWMAN.
